LE ROY J. DEKIN,
EGG BEATER.
APPLICATION FILED JULY 10, 1920.

1,437,133.

Patented Nov. 28, 1922.

UNITED STATES PATENT OFFICE.

LE ROY J. DEKIN, OF ILLION, NEW YORK.

EGG BEATER.

Application filed July 10, 1920. Serial No. 395,306.

To all whom it may concern:

Be it known that I, LE ROY J. DEKIN, a citizen of the United States, and a resident of Ilion, in the county of Herkimer 5 and State of New York, have invented certain new and useful Improvements in Egg Beaters; and I do hereby declare that the following is a full, clear, and exact description thereof, which will enable others skilled 10 in the art to which it appertains to make and use the same, reference being had to the accompanying drawings, and to the reference numerals marked thereon, which form part of this specification.

15 My present invention relates to a beating device particularly adapted to be used in beating eggs or whipping cream.

The purpose of my invention is to provide an improved device of the character described and one which is simple and economical in construction and durable and efficient in operation.

A further purpose is to provide a beating device operated through successive pulls 25 upon a cord being used to rotate a weighted wheel or balance wheel and which beating device is complete in itself and may be placed in any suitable bowl or other receptacle without having to be attached to the receptacle and without the receptacle 30 having any special parts or attachments to be engaged by the beater.

A further purpose is to provide an article of the class described having details of construction and arrangement of parts which insures ease of operation, cleanliness and strength.

Fig. 1 is a side view of a beating device embodying my invention as it would appear 40 in operation in a bowl.

Fig. 2 is a vertical central and longitudinal sectional view of the beater shown in Fig. 1.

Referring to the drawings in a more particular description it will be seen that the beater comprises a vertical shaft 5 having a handle 6 at its upper end, a weighted wheel or balance wheel 7 with an upwardly extended hub 8 mounted on the shaft towards its upper end and a beating blade or beating blades 9 rigidly secured to the wheel 7 and projecting downward therefrom.

The shaft 5 may conveniently be formed from a suitable length of small rod or stiff 55 wire bent in any desired way so as to pro-

vide a suitable handle 6 at the upper end of the shaft. Preferably also the same rod or wire from which the shaft is made is of sufficient length to provide an arm 10 projecting out from the shaft just below the handle 6 and then downwardly to a point opposite the middle of the hub 8 and there provided with an eye 11 for a purpose to be explained hereafter.

The weighted wheel or balance wheel 7 65 having the long upwardly extending hub 8 is mounted to be very freely rotated upon the shaft 5 towards the upper end of said shaft, but fixed from longitudinal movement upon said shaft. A convenient and 70 the preferred form of so mounting the wheel 7 is to provide upper and lower sleeves 12 and 13 respectively upon the shaft 5 above the upper end of the hub 8 and below the wheel 7. The lower end of the upper sleeve 75 12 and the upper end of the lower sleeve 13 are tapering or conical in form so as to project a short distance into the axial aperture or bore 14 of the wheel 7 and the long hub 8, it being understood that the bore 14 is of larger diameter than the shaft 5 which extends therethrough. In this way it will be seen the sleeves 12 and 13 provide 80 bearings at the upper and lower end of the combined wheel 7 and hub 8. These bearing sleeves 12 and 13 may be held in place upon the shaft 5 by set screws 15.

Secured to the wheel 7 preferably to the lower side thereof as by screws or other fastening means 16 are the beating blades 90 9. These blades may be of any desired form and number. In the drawing they are shown as two blades formed from one piece of metal bent into loop-shape with the two ends of the strip or piece of metal bent at right 95 angles so as to be readily fastened to the under surface of the wheel 7 by the screw 16. The lower end of this loop-shaped form of beater blades is rotatably mounted upon the shaft 5 close to its lower end by simply 100 providing a hole in the strip of metal forming the blades at that point.

To the hub 8 is secured one end of a flexible member such as a cord 17 which is threaded through the eye 11 in the depending arm 10 and has its free end outside said eye to be grasped by the operator for manual operation of the device.

The operation of my device is as follows: 105 The device will be placed in the bowl or 110

other receptacle 18 containing the eggs to be beaten or the cream to be whipped with the lower end of the shaft 5 resting upon the bottom of the bowl and with the device held 5 securely in place by the operator grasping the handle 6. The cord will first be wound up upon the shaft 8 and then the operator will give the free end of the cord a sharp pull which will obviously cause the weighted 10 wheel 7 to rotate rapidly carrying therewith the beater blades 9. After the cord has been entirely unwound from the hub 8 the momentum given the weighted wheel 7 from the previous pull will continue to make the 15 wheel 7 rotate in the same direction which will cause the cord 17 to be re-wound upon the hub 8 but in a direction reverse to that in which it was first wound thereupon.

After the cord is nearly re-wound upon 20 the hub 8 the operator holds back upon the free end of the cord enough to arrest the motion of the beater if it is not already stopped and then gives the cord another pull which operates to rapidly revolve the wheel 25 7 and its attached parts in the reverse direction. After the wheel has rotated in this direction sufficiently to unwind the cord therefrom the rotation of the wheel continues in the same direction sufficiently to 30 again re-wind the cord upon the hub, but in the opposite direction or in the way in which it was first wound upon the hub.

It will thus be seen that successive sharp 35 pulls upon the cord will operate to very rapidly rotate the beater blades successively in opposite directions.

It will be seen that the device is very simple and that the beater is complete of itself without having to be attached in any

special way to the receptacle 18 and without 40 requiring any special form of receptacle.

What I claim as new and desire to secure by Letters Patent is:

1. In a beating device the combination of a vertical shaft having a handle at its upper end to hold the shaft stationary, a relatively heavy wheel having an extended hub portion with a bore larger than said shaft, sleeves mounted on said shaft above and below said wheel with a conical end on 45 each sleeve entering said bore and affording bearings for said wheel, beating blades secured to and projecting downward from said wheel and a cord secured at one end to and adapted to be wound upon said hub of the 50 wheel whereby successive pulls upon the free end of the cord rotates the wheel and attached beater blades alternately in opposite directions, the lower end of the shaft projecting below the blades and adapted to 55 support the device by resting without rotation upon the bottom of a receptacle.

2. In a beating device the combination of a vertical shaft having a handle at its upper end to hold the shaft stationary, a relatively heavy wheel having an extended hub portion with a bore larger than said shaft, sleeves mounted on said shaft above and below said wheel with a conical end on each 60 sleeve entering said bore and affording bearings for said wheel, beating blades secured to and projecting downward from said wheel and means operatively connected with 65 said wheel for rotating the same.

In witness whereof I have affixed my 70 signature, this 23 day of June, 1920.

LE ROY J. DEKIN.
